PASSENGER VEHICLE FOR AMUSEMENT
DEVICES

Lavoy Winton, Mount Dora, Fla. 32757

Filed Jan. 27, 1966, Ser. No. 788

Term of patent 14 years

(Cl. D34—.5)

Fig. 1

Fig. 2

Fig. 3

Fig. 4

FIG. 1 is a perspective view of the passenger vehicle for amusement devices showing my design;

FIG. 2 is a top plan view of the vehicle shown in FIG. 1;

FIG. 3 is a bottom plan view of the vehicle shown in FIGS. 1 and 2;

FIG. 4 is a rear elevational view of the vehicle shown in FIGS. 1, 2 and 3.

The essential features of my design reside in the full line portions shown.

I claim:

The ornamental design for a passenger vehicle for amusement devices, substantially as shown and described.
